UNITED STATES PATENT OFFICE.

BEVERLY T. SNELLING, OF WASHINGTON, DISTRICT OF COLUMBIA.

FOLDABLE BOAT-CHAIR.

1,161,420.

Specification of Letters Patent. Patented Nov. 23, 1915.

Application filed August 3, 1914. Serial No. 854,712.

To all whom it may concern:

Be it known that I, BEVERLY T. SNELLING, a citizen of the United States, residing at Washington, in the District of Columbia, have invented new and useful Improvements in Foldable Boat-Chairs, of which the following is a specification.

This invention relates to improvements in portable chairs primarily for use in row-10 boats and the like.

In carrying out my invention I aim to produce a foldable chair which shall be light and portable and which may be easily and quickly attached to any seat in a boat and 15 effectively retained thereon.

It is also my purpose to provide a chair of this character which may be tilted to the comfort of the occupant when the chair is in attached position, and which is also revolu-20 ble so that the occupant of the chair may face any part of the boat without interfering with the chair securing means.

A further object of the invention is to provide a light and portable chair of this class 25 primarily intended for the use of fishermen which shall, when folded, serve as a receptacle or holder for fishing tackle and other accessories.

A still further object is to produce a fold-30 able and portable chair which shall be light and strong, simple, durable and cheap.

With the above and other objects in view, the improvement resides in the construction, combination and operative arrangement of 35 parts set forth in the following specification and falling within the scope of the appended claims.

In the drawings there is illustrated a simple and satisfactory reduction of the im-40 provement to practice, and in which:

Figure 1 is a perspective view of a chair constructed in accordance with my invention and showing the same applied to a boat seat, Fig. 2 is a central longitudinal section 45 through the same, Fig. 3 is a transverse section through the seat of the chair taken on a line with the support, and the clamping member swung flush with the support, Fig. 4 is a detail bottom plan view of the seat 50 showing the supporting member swung against the seat, Fig. 5 is a transverse section approximately on the line $\alpha-\alpha$ of Fig. 2, looking in the direction of the arrows, Fig. 6 is a detail perspective looking toward the 55 rear of the back, Fig. 7 is a perspective view of a modified form showing the same applied

to the seat of a boat, Fig. 8 is a perspective view showing the same folded, the brace links being removed, Fig. 9 is a central vertical longitudinal section of the device shown 60 in Fig. 7, Fig. 10 is a sectional view approximately on the line $b-b$ of Fig. 9, Fig. 11 is a perspective view of the supporting and attaching device, Fig. 12 is a fragmentary perspective view of a modification, Fig. 13 is 65 a fragmentary elevation of a still further modification, and Fig. 14 is a perspective view of the device illustrated in Fig. 13, the same being folded to provide a carrying case.

The chair may be constructed of any light 70 strong material and includes a bottom 1 and a back 2 which is hingedly connected with the bottom as indicated by the numeral 3. Pivoted links 4 arranged in pairs are connected to the side edges of the bottom and 75 back, as shown, to limit the swinging of the back and to relieve the hinges from unnecessary strain.

The side members or stiles 5-5 of the back in Fig. 6 have secured therebetween two 80 transverse rods 6-6 which receive straps 7-7 that are provided with buckles 8-8. These straps serve to fasten articles or packages which are desired to the back 2, as will be understood.

The side members 9-9 of the frame of the seat 1 are provided upon their under faces, each with diametrically oppositely arranged curved depressions 10-10 which enter from the inner edge of the said side members and 90 these depressions serve as bearing seats for trunnions 11-11 which project from the diametrically opposite corners of a rectangular bolster 12. The trunnions are retained in the depressions by plates 13. The 95 bolster is of a length approximately equaling the distance between the members 9-9 of the base and is also of a thickness equaling or less than the thickness of the said members, so that the bolster may be swung be-100 tween the said members when the chair is not set up (see Fig. 4).

Passing loosely centrally through the bolster is a headed bolt 14, which connects a clamp 15 with the bolster. This clamp 15 105 includes a substantially rectangular bar 16 which has its outer face provided with a metallic strap 17, the said strap having one of its ends bent and continued parallel with but spaced from the bar to provide what I 110 will term a jaw 18. The strap and jaw have a facing of soft material 19, so that the

same will not injure the seat 20 of a boat 21 when arranged upon the said seat. The jaw 18 is provided with a threaded orifice within which works the threaded stem of a 5 clamping screw 21'. By arranging the jaw upon one end only of the strap it will be noted that the chair can be secured not only to one of the central seats of the boat but also to the seat in the bow or to the seat in 10 the stern of the boat as desired. A washer 22 is arranged upon the pivot bolt 14 between the bolster 12 and the clamp to reduce the friction between these two members and permit the free revolving of the 15 chair.

The ends of the bolster 12 have secured thereon projecting straps 23-28 which serve as feet and which rest upon the boat seat 20 to prevent the side tilting of the 20 chair when the chair is in the position shown in Figs. 1, 2 and 5. These feet may be provided with protective strips to prevent the same marring the boat seat if desired.

25 By reference to Figs. 1 and 3 it will be noted that the side members 5-5 of the back 2 rest directly upon the bottom 1 at the rear of said bottom and consequently the bolster is of a slightly greater length than 30 the back, so that the rear end of the bottom will extend slightly beyond the back when the back is folded upon the bottom. The extending portion of the bottom is formed with an elongated hole 24 which serves as a hand hold whereby the folded chair may be gripped and conveyed as will be understood.

In Figs. 7 to 10 inclusive there is illustrated a slight modification of the chair and 10 the support therefor. The bottom 25 has its rear end, adjacent its corners provided with extending portions or lugs 26. Each of the side stiles of the frame of the back 27 has one of its ends curved and projects beyond 15 the back proper. The curved ends 28 and 29 are arranged against the outer sides of the lugs 26 and a pivot rod 30 is passed through the said ends and lugs. The central portion of the rod 30 serves as a hand 20 hold whereby the chair can be gripped and conveyed when folded. Brace links, arranged in pairs, connect the bottom 25 with the back 27. The links 31, which are connected to the bottom may be provided with 25 elongated slots adjacent their ends, while the links 32 which are pivoted to the back are provided with elongated slots adjacent their free ends. Headed studs 33 pass through the outer slots in the links 31 as 30 well as through the slots in the links 32 and thumb nuts 34 engage the threaded shanks of the said studs. By this means the back 27 may be swung to any desired angle with 35 relation to the bottom 25. The bolster 35 is 35 substantially similar to that previously de-

scribed and has its trunnions arranged in recesses in the side members of the frame of the bottom and retained therein by suitable plates also in the manner previously set forth. The clamp includes a centrally pivoted bar 36 which has connected, centrally, to its side faces the arms of a yoke 37. Two straps 38 and 39, one overlapping the other pass between the yoke and the bar. Each of these straps has its outer end bent to provide a jaw 40 (similar to the jaw 18) and each of the jaws has an adjustable clamping screw 41. In positioning the clamp upon the seat 42 of a boat 43, the straps are drawn outwardly of the yoke until after 70 their jaws pass the opposite edges of the seat, and they are then moved toward each other until their curved or bent portions contact the opposite edges of the seat. The clamping screws are then applied. This device can only be attached to the middle seats of the boat, and preferably only one of the straps is movable, the second being secured to the bar 36 and the movable strap having 75 its inner end offset as at 44 to prevent its entire passage through the yoke.

In Fig. 11 the bar 45 connected to the bolster 46, has its opposite sides channeled longitudinally and one of the straps 47 of one of the clamps has angular sides which have 80 their edges inturned to provide flanges 48 that ride in the channels. The second strap 49 is arranged between the sides of the first strap 47 and is preferably secured to the outer face of the bar 45. The curved jaw 85 portions of each of the straps have their ends slotted, and pivotally arranged within each of the slots is a cam lever 50.

In Fig. 12 the back 51 is shown hingedly secured to the bottom 52, the brace straps 10 being dispensed with.

In Fig. 13 I show the bottom 53 of a chair provided upon its sides and back with cleats 54, the back 55 being hingedly secured to the rear cleat.

In Fig. 14 I have shown the back folded upon the cleats over the bottom, a hook 56 engaging an eye 57, retaining the chair folded. With this construction the space 1 between the back and bottom (when the 1 chair is folded) provides for the reception of various articles and the chair is thus converted into a carrying case.

By reference to the several views it will be noted that the bars of the clamp are of a sufficient length to contact with the rear stile or member of the frame of the bottom, so that the same will not contact with the seat proper and inflict injury upon the same and it is desirable that the frames of the 1 backs disclosed in the several views be provided with the rods and straps disclosed in Fig. 6 so that, as previously stated, articles may be secured to the chair. It will be also noted that when the chair is in its folded 1

- position, the thumb nut of the clamp may be turned in an unscrewing direction to cause the head of the same to contact with one of the end bars or stiles of the bottom frame 5 which will serve to lock the support and clamp within the frame and overcome any tendency of the swinging thereof, when the device is transported, and from the foregoing, taken in connection with the accompanying drawings, the simplicity of the device, as well as the advantages thereof will, it is thought, be perfectly apparent to those skilled in the art to which such invention appertains without further detailed description.
- Having thus described the invention, what I claim is:
1. A chair of the class described, including a bottom, a back hinged to the bottom, adjustable link supports between the back and bottom, a bolster trunnioned to the bottom, and a clamp pivotally secured to the bolster.
  2. A chair of the class set forth including a bottom, a back resting on the bottom and hinged thereto, means for adjusting the outward swinging of the back upon the bottom, a bolster trunnioned with the bottom, and an adjustable clamp pivotally connected with the bolster.
  3. A chair of the class set forth, including a bottom frame, and a back frame which is hingedly secured to the bottom frame and rests at an angle thereon when in open position, the side members of the bottom frame having diametrically opposite depressions, a substantially rectangular bolster having its diametrically opposite corners formed with trunnions which are arranged within the depressions, plates covering the depressions, and a clamp centrally pivoted with the bolster.
  4. A chair including a bottom and a back hinged to the bottom, a bolster having trunnions mounted in bearings on the bottom, a bar centrally pivoted to the bolster, a strap secured to the bar, and said strap having an angular end providing a jaw and an adjustable securing element associated with the jaw.
  5. A chair including a hinged back and bottom, a bolster having trunnions mounted in bearings in the side bars of the bottom frame, feet extending from the ends of the bolster, a bar between the feet centrally pivoted to the bolster, a clamp associated with the bar, said clamp including an end jaw, and an adjustable securing member for the jaw.
  6. A chair having a rotatable support below the seat of the chair, and a pivoted clamp secured to said support.
  7. A chair having a swinging support below the seat of the chair and a revoluble clamp associated with said support.
  8. A chair having its bottom provided with a transverse swinging support, a revoluble clamp associated with said support, said clamp adapted to serve as a stop for the bottom of the chair when the clamp is revolved angularly of the support and the chair is tilted upon the support, and legs upon the support to sustain the chair against tilting in a sidewise direction.
  9. A boat chair adapted to be removably secured to the seat of a boat, including a bottom and a back hinged to the bottom, a swinging support arranged transversely of the bottom, a revoluble clamp upon the support adapted to engage with the seat of the boat, means provided upon the support and contacting the seat to prevent side tilting of the seat when the said seat is in one position, and means for limiting the swinging of the seat upon the support.
  10. A boat chair including a bottom frame and a back frame hinged to the bottom frame and resting thereon when the back is swung to an open position, a support journaled in bearings in the side members of the bottom frame, straps providing legs arranged upon the ends of the support between the side members of the bottom frame, a rectangular bar upon the support between the legs, a pivot bolt centrally connecting the bar to the support, a washer upon the bolt between the support and bar, a clamp including an angular jaw associated with the bar, a retaining screw for the jaw and said screw adapted to be operated in a retrograde direction to force the head of the same in contact with one of the end bars of the bottom frame to lock the support, bar and clamp in the frame, when the chair is in its folded position.
  11. A boat chair including a bottom frame and a back frame hinged to the bottom frame, a support journaled on the bottom frame, a clamp pivotally connected to the support, and bars secured to the side members of the back frame.

In testimony whereof I affix my signature in the presence of two witnesses.

BEVERLY T. SNELLING.
